UNITED STATES PATENT OFFICE.

ALPHONS GOTTHOLD GARDNER, OF LOS ANGELES, CALIFORNIA.

PRESSURE-BAR FOR PIANO-STRINGS.

1,375,146.

Specification of Letters Patent. Patented Apr. 19, 1921.

Application filed June 30, 1920. Serial No. 393,222.

To all whom it may concern:

Be it known that I, ALPHONS GOTTHOLD GARDNER, a citizen of the United States, residing in the city of Los Angeles, State of California, have invented Improved Pressure Bars for Piano-Strings, of which the following is a description.

The object of the invention is to hold more firmly those portions of certain treble strings of a piano which lie between the main bridge and the hitch pins, thereby changing more or less the pressure of the strings on the bridge.

In the accompanying drawing—
15 Figure 1 shows diagrammatically the treble end of a piano plate with strings.

Fig. 2 shows in perspective the pressure bar and screw.

Fig. 3 shows the bar in place on the 20 strings. Fig. 4 is a view at right angles to that of Fig. 3.

As Fig. 1 shows, a short block or bar 20 extends across the two triplets or sets of strings numbered 16 and 17 from the top. This bar is located between the main bridge 25 21 and the hitch pins 22 and is held in place by a screw 23 into the soundingboard, and presses the strings slightly closer to the sounding board, thereby preventing rattling and increasing their pressure on the bridge, 30 which in some cases improves the tone.

I claim—

A piano having a short pressure bar extending across the strings for two treble notes only, in the region of Nos. 16 and 17 35 from the top, said bar located between the soundingboard bridge and the hitch plate, and a screw drawing said bar toward the soundingboard, substantially as described.

ALPHONS GOTTHOLD GARDNER.
